UNITED STATES PATENT OFFICE.

JOHN FLETCHER FORD, OF HAWTHORNE, CALIFORNIA.

WINDMILL.

1,285,661.

Specification of Letters Patent. Patented Nov. 26, 1918.

Application filed March 23, 1918. Serial No. 86,081.

To all whom it may concern:

Be it known that I, JOHN FLETCHER FORD, a citizen of the United States, residing at Hawthorne, in the county of Los Angeles 5 and State of California, have invented certain new and useful Improvements in Windmills, of which the following is a specification.

This invention relates to improvements in 10 windmills, and especially to that class of windmills that are provided with vertically operating shafts and with vanes or blades adapted to operate around the said shaft and to be properly feathered to propel the 15 shaft under the action of the wind. The mechanism is of a type similar to that shown and described in my prior Letters Patent of the United States for improvements in windmills bearing Serial Number 20 561,074, and issued May 26, 1896.

It is an object of the invention to provide a windmill with a wheel structure having a plurality of feathering blades, adapted to be automatically set by the action of the 25 wind, for causing the rotation of the said wheel and the driving of the shaft carrying the same.

It is also an object of the invention to provide a windmill with vertically arranged 30 feathering blades or vanes, and to also provide a floating member suitably connecting with said vanes to secure a proper co-operating feathering of the blades with respect to each other, whereby those blades that are 35 in position to actuate the mill will receive the force of the wind while other blades which are not in a position to accomplish the proper operation, will be held out of the wind.

40 It is a further object of the invention to provide a windmill of this character in which the blades or vanes have crank arms, and in which a floating ring is employed having engagement with said crank arms, 45 such that the blades will be properly relatively feathered, a braking means co-operating with said floating ring for rendering the blades inactive and thus preventing the operation of the mill.

50 With these and other objects in view, the invention comprises certain novel combinations, constructions and arrangements of parts, as will be hereinafter more fully described and claimed.

In the accompanying drawing, forming a 55 part of this specification:

Figure 1 is a side elevation of a windmill constructed in accordance with this invention, the cover of the mill, being shown in section and the lower portions of the supporting frame being also broken away.

Fig. 2 is a transverse sectional view taken upon the line 2—2 of Fig. 1.

Fig. 3 is a fragmentary view showing the vane controlling floating ring in top plan, 65 and a portion of the wind wheel below.

Fig. 4 is a fragmentary view upon an enlarged scale of the upper end of adjacent vanes, showing the cranks carried thereby and engaging a floating ring, as well as 70 showing a ball bearing for supporting the ring.

Fig. 5 is a horizontal transverse sectional view taken upon the line 5—5 of Fig. 1.

Fig. 6 is a fragmentary detail view showing the mechanism for controlling the braking device used upon the wind wheel.

Fig. 7 is a fragmentary detail sectional view upon an enlarged scale taken upon the line 7—7 of Fig. 2.

The windmill of the present invention is designed to afford a mechanism in which a vertical shaft may be actuated and a wheel be employed, in which vertical vanes may be used and pivotally supported in a wheel 85 frame, the vanes being so mounted that those which can be set at a proper angle to communicate movement to the wheel may so act at the same time upon other vanes or blades as to arrange them so as not to offer 90 resistance to the air. The mechanism is of a character to automatically bring the vanes progressively into position to actuate the wheel.

In the accompanying drawings the preferred embodiments of the invention have been disclosed and the details and features of said invention will now be set forth, reference being had to said illustration.

Referring with particularity to the drawings the frame 10 comprises the uprights having horizontal frame bars 11 at the top thereof, and horizontal braces 12 at intermediate points on the frame 10; the frame 10 may be constructed of any suitable material and of various formation in accordance with the usual derricks or frames of this character employed.

A shaft 13 extends vertically of the frame 10 and is rotatably mounted in journals 15 and 16 provided therefor.

The wind-wheel 17 specifically comprises a frame 18 fixed to the shaft 13 and formed with ring portion at the top and bottom thereof. Blades or vanes 19 of relatively thin formation are mounted within the ring portions 18 of the said wheel 17, pivoted members, 20, being provided and fastened adjacent one side edge 21 of each blade. Each of said members 20 is provided with the relatively reduced end pivotally engaging bearings in the bottom ring 18. The upper end of each of said blades or vanes 19 is provided with a bracket 22 having a portion thereof journaled in said upper ring 18 and each of said brackets has the lever or crank arm 23 extending therefrom and ranging above the upper surface of said upper ring 18. The blade controlling means comprises said lever arms 23 in connection with said brackets 22, said arms having the pins 24 extending therefrom the latter fitting within suitable slots 26 provided in a floating-ring or drag-link 25. The link 25 is preferably wider than the upper ring 18 of the frame 10 and the slots are of predetermined formation and so arranged that when the wind moves the blades or vanes, the levers 23 are moved to thereby move the pins 24, and thereby shift the link a predetermined distance, to set the blades or vanes in the desired manner substantially as shown in Figs. 2 and 3 of the drawings. Suitable roller or ball bearings 27, may be provided on the upper ring 18 such bearings 27 preferably having a ball 28 therein, thereby partially eliminating the friction in moving said floating-ring or drag-link 25 and facilitating the easy movement of the same.

A braking means for the wheel is also provided and comprises a plate 30 journaled on the upper end of the shaft 13, to which plate the ends 31 of the links 32 are pivotally connected. The links 32 extend to levers 33 which are carried by the upper ends of crank members 35 having brake ends or shoes 36 adapted to be moved into contact with the floating-ring or drag-link 25 when properly operated. A plate 30 is connected by a cable 37 with a spring 38 mounted upon the central upper frame bar 11 as shown in Fig. 2 of the drawing, the action of the said spring normally pulling upon the plate 30 so that the shoe ends 36 of the said cranks 35 will normally be swung out of engagement with the inner edge of the floating ring 25. In order to apply the brakes, a cable 39 is connected with said plate 30 and passed over a pulley 40 on one of the upper corners of the frame 10, the said cable passing thence downwardly to a windlass mechanism comprising a small drum 41 operated

by a crank 42, and having a ratchet 43 adapted to be engaged by a pawl 44 for holding the drum when the cable is wound thereon. By winding the cable on the drum, the plate 30 can be turned against the action of the spring 38 for causing the crank members 35 to so move as to press the shoe portions 36, against the inner periphery of the floating ring or link 25. This will not only stop the movement of the said link with the wind wheel, but will also center the said ring with respect to the shaft 13, whereby the blades or vanes 19 will all be moved to their inoperative positions as clearly shown in Fig. 3 of the drawing. While the blades are held in this position, the wind will no longer affect the same in a way to move the wind wheel. When it is desired to permit the wind to operate the wheel again, the cable 39 is released and the pressure of the wind will again push inwardly the vanes upon the windward side of the wheel and at the same time push outwardly the vanes upon the lee side for actuating the said wheel, as shown in Figs. 1, 2 and 3 of the drawing.

The means for transferring movement from the windmill shaft may be of any desired type. The transmission means illustrated in the drawings comprises a short shaft 45 journaled in a frame 46 and preferably extending at right angles to the shaft 13 of the windmill. A bevel gear 47 fixed to the shaft 45 meshes with an actuating bevel gear 48 secured to the said shaft 13. A pulley 49 secured to the shaft 45 may be used to transmit the power developed in the mechanism to any other mechanism or machine, by suitable belting, not shown. In order to disconnect the transmission mechanism from the windmill shaft when desired, the said shaft is so mounted in its bearings that it may be moved longitudinally. A lever 50 is pivotally connected to the outer end of said shaft 45 and is fulcrumed at 51 on the frame of the machine for reciprocating the said shaft 45 and thereby disconnecting the bevel gears or bringing them into mesh again as the case may be. A lever latch mechanism 52 is carried by the said lever 50, the notches 53 of which engage a pin 54 carried by the frame 46 whereby the lever may be locked for holding the gear 47 whether in working or idle position. In the operation of the device, the cable 39 is unwound from the drum 41 whereby sufficient slackness therein is permitted to allow the spring 38 to swing the crank members 35 inwardly and out of contact with the floating ring 25. The vanes on the side of the wheel next to the wind, will then be pushed inwardly to the extent permitted by the floating action of the said ring 25, the said vanes being thus set at angles ap-

proximating forty-five degrees to the direction of movement of the wind. The floating ring being thus moved will also set the vanes upon the lee side of the wheel in a correspondingly angular position with the result that the front and back vanes will be moved by the wind to turn or drive the wind wheel. The slots 26 in the floating ring, being arranged substantially in the circular direction of the ring itself, will at the same time hold the vanes at the sides of the wheel, when considering the position of the wheel, as related to the direction of the wind, so as to keep the said vanes in edgewise relation to the wind, whereby the said vanes will offer practically no resistance at all points where such resistance would retard the movement of the wind wheel. The position of the floating ring will of course be considerably changed under the action of the front vanes as they are forced inwardly by the direct impact of the wind, whereby the front and rear vanes will be actuating the wind wheel, while the other vanes will be kept out of the wind. When the wheel is to be stopped the cable 29 is wound again upon the drum 41 for pulling the shoe ends 36 of the crank members 35 against the inner edge of the said floating ring. The said ring will thus be caused to stop the wheel and will also be centered as shown in Fig. 5, whereby all the vanes will be set substantially in line with the upper and lower links 18 of the wind wheel 17, and the wind will have no action upon the same for turning the wheel.

It will be observed that with the wheel of this kind, the direction in which the wind comes will be a matter of no importance for the vanes will be operated no matter what the direction of the wind, and the floating ring will automatically further set the vanes in accordance with the direction of said wind. It will be observed therefore that the wheel will be effective no matter whether the wind is a steady one or whether it is changeable and of a gusty character. The wheel because of its simple structure will also be strengthened and not readily injured by strong winds. The size of the windmill and of its wheels may of course be varied within the spirit of the invention and while an even number of blades have been shown in the drawings, it will be evident that any desired number may be employed without departing in the least from the spirit of the invention.

What is claimed is:

1. A windmill comprising a wind wheel, a shaft carrying the same, and a plurality of vanes carried by said wheel and extending parallel with said shaft and a drag ring member having a pin and slot connection with each of the said vanes, whereby move-

ment imparted to some of the vanes by the action of the wind will be caused to set other vanes in proper position for not retarding the action of the wind wheel.

2. A wind mill comprising a wind wheel mounted on a vertical shaft; a plurality of vanes pivoted in said wind wheel, a floating member connecting the said vanes, arms carried by said vanes and having a slotted connection with said floating member for projecting the same at various angles of incidence; and braking means for stopping or locking said wind-wheel.

3. A wind mill comprising a wind wheel mounted on a vertical shaft; a plurality of vanes pivoted in said wind wheel; a floating member, crank means interposed between said vanes and said floating member for changing the angles of incidence thereof to increase or decrease the projected areas thereof; and braking means for stopping and locking said wind wheel from rotation.

4. A wind mill comprising a wind wheel mounted on a vertical shaft; a plurality of vanes pivoted in said wind wheel; a drag-link in connection with said vanes, crank members connecting said drag-link with each of the vanes for changing the angles of incidence thereof to increase or decrease the projected areas thereof; power transmission means; and braking means for stopping and locking said wind wheel from rotation.

5. A wind mill comprising a wind wheel, a vertical shaft carrying the same, a plurality of vanes pivoted upon the wind wheel, a floating drag link member connecting all of the said vanes and having means whereby it is moved by some of the vanes for setting to correspond therewith, and a braking means engaging said link for stopping or locking the wind wheel.

6. A wind mill comprising a suitable frame having a wind wheel mounted on a vertical shaft therein; a plurality of vanes pivoted in said wind wheel; a controlling drag link having a crank and slot connection with each of said vanes for projecting the same at varying angles of incidence; power transmission means; and braking means for regulating the velocity of said wind wheel or stopping and locking the same from rotation.

7. A wind mill comprising a wind wheel having vertically arranged feathering blades pivoted therein, crank members carried by said blades, a floating member having slots therein adapted to engage said crank members, whereby the vanes will be automatically set by the action of the wind for securing the turning of the wheel.

8. A wind mill comprising a frame, a vertical shaft journaled therein, a wind wheel carried by said shaft, a plurality of vanes journaled in said wind wheel, a float-

- ing member having a pivoted connection with the said vanes, and breaking means engaging the said floating member for preventing its floating movement and thereby stopping the wheel.
9. A wind mill comprising a suitable frame; a vertical shaft in said frame; a wind wheel on said shaft; a plurality of vanes pivotally arranged in said wind wheel; a drag link having slots therein, arms projecting from said vanes and having wrist-pins engaging said slots for projecting the vanes at various angles of incidence to increase or decrease the projected areas of said vanes; pump connecting means on said shaft; and braking means for stopping and locking said wind wheel from rotation.
10. A wind mill comprising a suitable frame; a vertical shaft in said frame; a wind wheel on said shaft; a plurality of vanes pivotally arranged in said wind wheel; a drag link operatively connecting the vanes with each other for projecting the same at various and predetermined angles of incidence to increase or decrease the projected areas of said vanes; pump connecting means on said shaft; transmission means in connection with said shaft; and braking means bearing upon said drag-link for stopping and locking said wind wheel from rotation.
11. A wind mill comprising a suitable frame; a vertical shaft in said frame; a wind wheel on said shaft; a plurality of vanes pivotally ranging in said wind wheel; a drag ring having slots therein for connection with the pivots of said vanes for projecting said vanes at varying angles of incidence to thereby increase or decrease the projected areas of said vanes; and braking cranks bearing against said drag-link means for regulating the velocity of said wind wheel in winds of varying velocities and for stopping or locking said wind wheel from rotation, substantially as described.
12. A wind mill comprising a suitable frame; a vertical shaft in said frame; a wind wheel on said shaft; a plurality of vanes pivotally ranging in said wheel; a drag link having slots therein for connection with the pivots of said vanes for projecting said vanes at varying predetermined angles of incidence to thereby increase or decrease the projected areas of said vanes; power transmission means in connection with said shaft; and braking means for regulating the velocity of said wind wheel in winds of varying velocities and for stopping or locking said wind wheel from rotation, substantially as described.
13. A wind mill comprising a suitable frame; a vertical shaft in said frame; a wind wheel on said shaft; a plurality of vanes pivotally arranged in said wind wheel; a drag link having slots therein for connection with the pivots of said vanes for projecting the latter at predetermined varying angles of incidence to thereby increase or decrease the projected areas of the vanes in their relation to each other; means for connecting the shaft to a pump and braking means for regulating the velocity of said wind wheel in winds of varying velocities and for stopping or locking said wind wheel from rotation, substantially as described.
14. A wind mill comprising a suitable frame; a vertical shaft in said frame; a wind wheel on said shaft; a plurality of vanes pivotally arranged in said wind wheel; a drag link having slots therein for connection with the pivots of said vanes for projecting the latter at predetermined varying angles of incidence to thereby increase or decrease the projected areas of the vanes in their relation to each other; means for connecting the shaft to a pump and braking means for regulating the velocity of said wind wheel in winds of varying velocities and for stopping or locking said wind wheel from rotation, substantially as described.
15. A wind mill comprising a suitable frame; a vertical shaft in said frame; a wind wheel on said shaft; a plurality of vanes pivotally arranged in said wind wheel; a drag link having slots therein for connection with the pivots of said vanes for projecting the latter at predetermined varying angles of incidence to thereby increase or decrease the projected areas of the vanes in their relation to each other; means for connecting the shaft to a pump and braking means normally out of contact with said drag link for regulating the velocity of said wind wheel in winds of varying velocities and for stopping or locking said wind wheel from rotation, substantially as described.
16. A wind mill comprising a suitable frame; a vertical shaft in said frame; a wind wheel on said shaft; power transmission means in connection with said shaft; a plurality of vanes pivoted at predetermined points circumferentially in said wind wheel; a drag link having slots therein for connection with the pivots of said vanes for projecting the latter at predetermined varying angles of incidence to thereby increase or decrease the projected areas of the vanes in their relation to each other; means for connecting the shaft to a pump; and braking means normally out of contact with said drag link for regulating the velocity of said wind wheel in winds of varying proportions in their relation to each other; means for connecting the shaft to a pump; and braking means normally out of contact with said drag link for regulating the velocity of said wind wheel in winds of varying velocities and for stopping or locking said wind wheel from rotation, substantially as described.
17. A wind mill comprising a suitable frame; a vertical shaft in said frame; a wind wheel on said shaft; power transmission means in connection with said shaft; a plurality of vanes pivoted at predetermined points on said vanes which range circumferentially in said wind wheel; a drag link having slots therein for connection with the pivots of said vanes for projecting the latter at predetermined varying angles of incidence to thereby increase or decrease the projected areas of the vanes in varying proportions in their relation to each other; roller

bearings for said drag link; means for connecting the shaft to a pump; and braking means normally out of contact with said drag link for regulating the velocity of said wind wheel in winds of varying velocities and for stopping or locking said wind wheel from rotation, substantially as described.

In testimony whereof I have hereunto set my hand in presence of two witnesses.
